UNITED STATES PATENT OFFICE.

ALWYNE F. JEALOUS, OF ROCHDALE, MASSACHUSETTS.

CARDING-MACHINE.

1,146,711.

Specification of Letters Patent. Patented July 13, 1915.

Application filed January 31, 1914. Serial No. 815,830.

To all whom it may concern:

Be it known that I, ALWYNE F. JEALOUS, a citizen of the United States, residing at Rochdale, county of Worcester, State of Massachusetts, have invented an Improvement in Carding-Machines, of which the following description, in connection with the accompanying drawing, is a specification, like characters on the drawing representing like parts.

This invention relates to improvements in textile machines such as carding machines which comprise mechanism for separating the material being treated, such as a lap of carded material, into strands, or which maintains several strands of material in a separated condition.

In carding wool, silk, and like materials and particularly in utilizing the waste from woolen, worsted and silk mills, the material is passed through a carding mechanism of the usual construction having doffing mechanism which divides the web of carded material into a series of strands of roping which are usually carried through suitable condensers and thence through suitable guides to spooling or other winding mechanism upon which they are wound in the usual manner, the spooled material being thereafter treated in any desired manner. It frequently happens that wandering fibers extend from one strand of roving to another, and as the several strands are being reeled upon the winding mechanism these fibers will engage the guides which direct the strands to the winding mechanism, and frequently being of greater strength than the strand itself will break or injure the roving.

One of the objects of the present invention is to provide means which will sever the fibers connecting one strand of roving to another without injuring or breaking either of the strands of roving to which the fiber is attached, and to accomplish this result means have been provided whereby such fibers will be burned in two thus avoiding the placing of any substantial tension upon the strands of roving to be wound.

Another object of the invention is to provide means whereby the mechanism utilized for burning off the wandering fibers will not scorch or injure the adjacent edges of the strands of roving.

Other objects of the invention and the nature thereof will more fully appear from the following description and the accompanying drawings and will be particularly pointed out in the annexed claims.

In the drawings, Figure 1 is an end view of the winding frame with my invention attached thereto illustrating the relative position of the condenser, the winding mechanism and the means for severing the wandering fibers which extend between the strands of roving. Fig. 2, is a front elevation of a series of electric incandescent elements arranged between the strands of roving. Fig. 3 is an end view of the same, showing in section the support for the incandescent elements. Fig. 4 is a view of a modified form of my invention illustrating the incandescent elements as arranged in planes substantially at right angles to those shown in Fig. 2, that is in planes parallel to the direction of movement of the strands of roving. Fig. 5 is a vertical sectional view on lines 5—5, Fig. 4. Fig. 6 is a perspective view of a support for the incandescent electric element illustrated in Figs. 4 and 5. Fig. 7 is a plan view of a modified form of support for the incandescent element. Fig. 8 is a sectional view of the element illustrated in Fig. 7, taken on lines 8—8 of said figure.

The preferred embodiments of my invention are illustrated herein as adapted for use in connection with a carding machine of the usual type having one or more doffers adapted to deliver the carded material in a series of parallel strands of roving. Inasmuch as the carding machine is of a usual construction it is not illustrated in the drawing. From the doffers the strands of roving are delivered to condensing aprons 1, 2, of the usual type whence they are carried to suitable receiving mechanism preferably a spool 3 which is suitably supported upon the winding frame.

The winding frame as illustrated herein comprises vertical standards 4 having two or more lateral projections 5 provided with journals 6 adapted to support drums 7 upon which the spools rest and by which they are driven. Extending from the opposite side of the frame 4 are suitable brackets 8 which form supports for a series of guides 9 preferably mounted in a vertical position upon a rod 10. The aforesaid mechanism is of

the usual character and forms no part of my invention.

It is found in practice that in winding strands of roving of the character above described, wandering fibers frequently extend from one strand to another, and that such fibers engaging the guides 9 as the strands are being wound upon the spool offer sufficient resistance to injure or break one or both the strands.

In the use of long wools and of waste material from worsted, silk, and the like the roving is of a very loose character and is very easily torn apart, it is therefore necessary that the means for severing the fibers connecting one strand of roving to another be of such a character as to offer practically no resistance to the forward movement of the strands.

20 In the preferred embodiment of the invention illustrated herein such a severing means is provided by interposing an incandescent element intermediate of the strands of roving. This incandescent element may 25 be of any well known character but is preferably constructed of a wire having a relatively high electrical resistance and adapted to be made incandescent by an electric current of the ordinary strength and potential.

30 In the particular embodiments of the invention illustrated in the drawings brackets 12 are suitably attached to the bracket 8, or to the rods 10, which may be moved back and forth, and serve to support bars 13 in 35 front of and parallel to the guide supports 10. The bars 13 may be of wood provided with a covering of asbestos or other insulating material 14 to support a series of electric conductors spaced at suitable intervals 40 to permit the several strands of roving to pass between them.

As illustrated in Fig. 2 the conductors 15 are in the form of short plates having intervening spaces 16 insulating the successive 45 blocks from one another. The ends of the conductors 15 are connected by upwardly extending loops of wire 17 of suitable material of high resistance, said loops being located intermediate of the strands of roving 18. The end plates 15 are connected to 50 binding posts 19, which are connected by wires 20 to any suitable source of electric energy. It will be seen that the several strands of roving in passing between these 55 wires which are rendered incandescent by the current will be maintained wholly separated from one another since any wandering fiber which extends from one strand of roving to another upon coming in contact 60 with an incandescent wire will be instantly burned off without creating any such tension upon the strand as to injure or destroy it.

Another embodiment of my invention is illustrated in Figs. 4, 5, and 6 in which the 65 loops of wires are arranged in planes sub-

stantially parallel to the direction of movement of the strands of roving. In this form of my invention the supporting bar 13 may be covered with an insulating covering 14 such as asbestos as in the device shown in 70 Figs. 2 and 3. A series of brackets or stands are mounted upon the bar 13, such brackets or stands being preferably in the form illustrated in Figs. 5 and 6 and comprising a body portion 21 with upwardly projecting 75 lugs 22 containing apertures 23 for the reception of the ends of the loop of wire which constitutes the incandescent member. The lower portion of the body 21 is preferably provided with a pair of legs 24 extending 80 under a portion of said body intermediate of the upstanding lugs 22. This construction is adapted to permit a free circulation of air about the supporting member and to thereby prevent the same from becoming 85 overheated by the conduction of heat from the incandescent wire. The wire loops which form the incandescent members of the invention as illustrated in Figs. 4, 5, and 6 are preferably constructed of sections, one of 90 which is a relatively good conductor of electricity, while the other is of relatively high resistance. The ends of the loop are anchored in the upstanding lugs 22 and it has been found in practice that the same 95 may be securely fastened in said lugs by merely inserting the wire in the apertures 23 and thereafter squeezing the upper end of the lugs tightly upon said wires by means of a pair of pincers. Each of the loops 100 aforesaid preferably comprises a section 25 of brass spring wire, and a section 26 of a smaller wire, of relatively high electrical resistance and of material not easily oxidized when heated to incandescence, such as 105 "nickrome" wire. The section 25 of the loop is preferably slightly arched as illustrated in Fig. 5 and bent over at the top to support the upper end of the section 26 in such a manner as to impose a slight tension 110 upon the latter and thereby maintain the same at all times in a vertical position. The supporting members 21 are preferably arranged in the manner illustrated in Fig. 4 so that the electric current will pass through 115 said wires in series. As shown in Fig. 4 the supports 21 are arranged in staggered relation so that the ends of the successive supports overlap just enough to bring the wires connecting said ends into planes parallel to 120 the direction of movement of the strands of roving. The sections 26 being of course on the front side so that the wandering fibers will be burned off upon contact with said incandescent sections 26.

Another form of the invention is illustrated in Figs. 7 and 8 in which the incandescent wires are supported upon an insulating body or post, the incandescent section of the wire being preferably partially embed- 130

ded in a vertical groove extending along the side of the insulating member. As illustrated in these figures the insulating member consists preferably of a cylindrical post 5 having a lateral extension at its bottom 30 provided with an aperture adapted to receive a screw 32 to secure the same to the bar 13. The cylindrical member is preferably provided with a vertical aperture 33 adapted 10 to receive a suitable conductor of copper or brass wire 34 and if desired the wire may be cast within the insulating member. The outer portion of the cylindrical insulating member is preferably provided with a groove 15 35 adapted to partially inclose a section of wire 36 of relatively high resistance such as "nickrome" aforesaid. The conductors 34 and 34^a may be led from the base of the cylindrical insulating members to suitable 20 binding posts 37 whereby they may be arranged in series as aforesaid.

When the device as illustrated in Figs. 5 and 6 is placed in position upon the winding frames the posts will be mounted intermediate the strands of roving, the incandescent wires 36 being in planes intermediate of and substantially equidistant from the edges of the adjacent strands. In the operation 25 of the machine the insulating members or posts will prevent the edges of the strands from being sufficiently deflected to encounter the wires and be singed thereby but any wandering fiber which extends from one strand to another will during its movement 30 toward the winding mechanism encounter the incandescent member 36 and be severed in the manner aforesaid.

It is to be understood that the embodiments of the invention shown herein are 40 illustrative merely and that the same may be incorporated in other constructions. It is also to be understood that this invention may be utilized in other relations than those described herein since it is adapted to maintain 45 strands of any suitable material which are directed from one part of the machine to another or from one machine to another in a separated condition. It will also be obvious that the form of incandescent members herein are adapted to different uses, that illustrated in Figs. 7 and 8 being particularly adapted to be used in connection 50 with singeing machines since whatever the arrangement of the insulating member the incandescent wire will be supported through 55 its length and thereby maintained in uniform relation to the material being singed notwithstanding the expansion by the heat required to raise the same to incandescence 60 and further by reason of the fact that circumferential adjustment of the incandescent member would provide means for supporting the fiber in such a position that it may be caused to travel in any degree of proximity 65 to the incandescent member.

Having thus described my invention, what I claim as new and desire to secure by Letters Patent is:

1. The combination of mechanism for treating fibrous materials comprising means for delivering a plurality of strands of said material and means for receiving said strands, of means intermediate of said strand means and said receiving means for burning off fibers extending from one strand 75 to another.

2. In combination with mechanism for treating fibrous materials comprising means for delivering a plurality of strands of said material, and means for receiving said strands, and means intermediate said delivering means and said receiving means for severing fibers extending from one strand to another comprising an incandescent electric conductor, and means for supplying a 85 suitable electric current to said conductor.

3. In combination with mechanism for treating fibrous materials comprising means for delivering a plurality of strands of said material, and means for receiving said strands and means intermediate said delivering means and said receiving means for severing fibers extending from one strand to another comprising an incandescent electric conductor, means for supplying an electric 95 current to said conductor and means for maintaining the conductor under tension whereby distortion of the same by expansion will be prevented.

4. In combination with a carding machine comprising carding mechanism, doffing mechanism adapted to deliver the carded material in a plurality of strands of roving and means for receiving said strands, of means for severing fibers extending from one strand of roving to another comprising 100 a series of incandescent electric conductors positioned between adjacent strands of roving.

5. In combination with a carding machine comprising carding mechanism, doffing mechanism adapted to deliver carded matter in a plurality of strands of roving and winding mechanism therefor including a frame and guides supported thereby to direct the several strands of roving, means supported in advance and intermediate of said guides adapted to sever fibers extending from one strand to another without injuring or breaking the strands of roving. 110

6. In combination with a carding machine comprising carding mechanism and doffing mechanism adapted to deliver the carded material in a plurality of strands of roving, of winding mechanism comprising a frame, a guide support and guides mounted thereon adapted to direct the several strands of roving to a suitable spool, an insulated member mounted upon said guiding frame and in advance of said guides, incandescent 125

electric conductors carried by said insulated member and disposed intermediate of said strands in advance of said guides and means for supplying electric current to said conductors.

7. In combination with a carding machine having carding mechanism, and doffing mechanism adapted to deliver the carded material in a plurality of strands of 10 roving, and winding mechanism comprising a frame, a guide support, guides mounted thereon adapted to direct the several strands of roving, of an insulated member mounted upon said guide support in advance of said 15 guides, a pair of electric conductors carried

by said insulated member, means connecting said conductors, located between adjacent strands of roving, adapted to be rendered incandescent by an electric current to sever the fibers extending from one strand to another, and means for supplying an electric current to said conductors. 20

In testimony whereof, I have signed my name to this specification, in the presence of two subscribing witnesses.

ALWYNE F. JEALOUS.
